Application September 28, 1948, Serial No. 51,555

17 Claims. (Cl. 62—119.5)

1

The present invention relates to the art of refrigeration and more particularly to refrigerating apparatuses of the absorption type particularly designed to produce refrigeration at various temperature levels suitable for the preservation of fresh food stuffs, for the production of ice and for preservation of sharp frozen food stuffs. This application contains certain subject matter originally disclosed in my Patent 2,489,752, issued on November 29, 1949 for Refrigeration and to that extent is a continuation-in-part of my aforesaid application.

The present invention particularly relates to refrigerating apparatus of the absorption type in which low temperature refrigeration is produced by flowing highly purified liquid refrigerant into the presence of inert gas having an extremely low refrigerant vapor content.

It is a particular object of the present invention to provide a refrigerating system in which absorbing solution denuded of refrigerant in a generator is passed first into intimate contact with a comparatively small volume of inert gas having an initial low refrigerant vapor content under most efficient absorbing conditions to strip the small volume of inert gas of refrigerant vapor to produce an inert gas having a very low refrigerant vapor content which inert gas is then utilized to produce the extremely low temperature refrigeration. The aforesaid process does not greatly add to the refrigerant content of the solution because of the small volume and low refrigerant content of the inert gas involved; hence the solution is still capable of absorbing refrigerant vapor. The partially enriched solution is then led into contact with another, and larger, body of inert gas having a refrigerant vapor content greater than the refrigerant vapor content of the first body of inert gas to absorb an additional greater quantity of refrigerant vapor before returning to the generating apparatus to complete its cycle.

Other objects and advantages of the invention will become apparent as the description proceeds when taken in connection with the accompanying drawing in which:

Figure 1 is a vertical sectional side elevation of a refrigerator cabinet with a refrigerating apparatus shown partly schematically associated therewith;

Figure 2 shows a modified form of the invention;

Figure 3 illustrates a second modified form of the invention; and

Figure 4 illustrates another modified form of

2

the invention shown associated with certain cabinet constructions with which it will be used in operation.

Referring now to the drawing in detail and first to Figure 1 thereof, the refrigerating apparatus shown is of the inert gas absorption type which is charged with a refrigerant such as ammonia, an absorbent therefor such as water and a pressure equalizing medium which is inert with respect to the refrigerant and absorbent such as nitrogen.

The apparatus comprises a generator B containing a solution of refrigerant in the absorbent. The boiler is heated by suitable means, not shown, to evolve refrigerant vapor from the solution. Vapor so evolved in the generator B passes upwardly through an analyzer D in which it is brought into intimate contact with rich solution supplied from a source to be described hereinafter. After passing through the analyzer the vapors are conducted by a conduit 11 to a primary condenser C wherein the vapors are liquefied by heat exchange with atmospheric air. Liquid so produced flows through a liquid sealed gas trap 12 into a jacket 13 which surrounds the conduit 11. Since the liquid supplied to the jacket 13 is in direct contact with the pipe 11 carrying the hot vapors to the condenser the vapors are rectified and some of the liquid is vaporized to provide highly purified refrigerant vapor. This refrigerant vapor is substantially anhydrous ammonia and is suitable for extremely low temperature refrigeration. The anhydrous vapors formed in the jacket 13 flow through a conduit 14 into the upper portion of a secondary condenser C' wherein they are re-condensed and are conveyed through a conduit 15 into a low temperature evaporator conduit 16.

As shown herein the conduit 16 is simply a substantially horizontal sinuous conduit. It may however take any desired shape or configuration depending upon the particular type best suited to a specific design requirement.

Liquid refrigerant which is not evaporated in the jacket 13, the major portion of the refrigerant liquid, is conducted therefrom by a conduit 18 into the lower portion of a primary evaporator 19 to be described more fully hereinafter.

Lean absorbing solution formed in the generator B by the evolution of refrigerant vapor flows therefrom through a conduit 20, the outer passage of a liquid heat exchanger 21, a finned sinuous conduit 22 which forms a solution pre-cooler into a solution reservoir S. The absorbing solution is then conveyed for the reservoir S

55

through a U-shaped conduit 24 having a vertically extending, finned, leg 25 adapted to function as a gas lift pump and secondary absorber. Pumping gas is supplied through the conduit 25 from an inert gas circulating pump F which is driven by an hermetically sealed electrical motor drive M. Inert gas under pressure discharges from the pump F through a conduit 26 forming part of a principal inert gas circuit to be described hereinafter. A portion of the gas under pressure supplied to the conduit 26 is diverted through the conduit 27 which supplies pumping gas to the gas lift pump absorber 25.

The inert gas supplied to the conduit 27 is what is ordinarily termed in this art lean gas, that is, it is inert gas which has traversed an absorber for the purpose of removing refrigerant vapor therefrom, hence its refrigerant vapor content is small, however, this gas when introduced into the conduit 25 is brought into the most intimate possible contact with the leanest absorbing solution available in the system. In the conduit 25 the pumping gas is most intimately admixed with the lean solution. Additionally, the volume of inert gas supplied to the conduit 25 is comparatively small compared to the volume of inert gas which is ordinarily brought into contact with absorbing solution in the absorber of refrigerating systems of the type forming the subject matter of the present invention.

It has been found by experiment that the conduit 25 is a most efficient absorber under the foregoing conditions, that is, conditions in which the volume of inert gas is small compared to the volume of absorbing solution with which it is brought into intimate contact. It has additionally been found that the pumping gas supplied to the conduit 25, though what is customarily denominated as lean gas in this part, has its refrigerant content very appreciably lowered in its passage through the combined gas lift pump and secondary absorber conduit 25. The inert gas used to operate the pump-absorber 25 will have an absolute refrigerant vapor content as low as one percent by volume. The increase in the refrigerant content of the absorbing solution which traverses the conduit 25 represents the refrigerant vapor which it has absorbed from the pumping gas. This increase in refrigerant content of the lean solution will customarily not amount to more than approximately five percent whereas the total solution concentration range between the weakest and strongest solutions available in the system will vary approximately twenty to twenty-five percent, hence the enrichment which occurs in the pumping conduit 25 is comparatively small. The highly stripped inert gas which discharges into the gas separation chamber 28 along with the lean absorbing solution is ideal for the production of low temperature refrigeration due to its extremely low refrigerant vapor content which will permit extremely low temperature evaporation of refrigerant thereinto.

The inert gas which discharges into the chamber 28 is conducted to the low temperature evaporator 16 by means of a conduit 30 which passes in heat exchange relationship with the inert gas discharge conduit 31 of the evaporator 16 and in heat exchange relationship with the primary evaporator 19. This two stage cooling of the inert gas enroute to the low temperature evaporator 16 almost completely condenses vapors of absorbing solution and also supplies very cold gas to the low temperature evaporator 16 so that

that evaporator is not called upon to carry a substantial load which represents merely cooling of the inert gas. Condensate formed in conduit 30 drains back to chamber 28 or is removed to the strong solution conduit 34 by a drain conduit 32. The inert gas and liquid refrigerant supplied through the conduits 30 and 15 respectively to the evaporator 16 produce refrigeration therein at extremely low temperatures in the order of 5° F. and therebelow which are sufficient for the preservation of sharp frozen foods. It is to be borne in mind in this connection that the quantity of inert gas supplied to the evaporator 16 and the quantity of liquid refrigerant supplied thereto are both small compared to the quantity customarily supplied to these evaporators in domestic refrigerating apparatuses. The evaporator 16 maintains extremely low temperatures but it is not normally called upon to sustain a heavy refrigerating load because food stuffs which are placed in its compartment for preservation are almost invariably already thoroughly frozen and need only be maintained at a low temperature.

The absorbing solution supplied to the separation chamber 28 flows therefrom through a U-shaped gas sealing conduit 33 into the upper end of a tubular air-cooled absorber A. As shown in Figure 1 this is a conventional type of tubular air-cooled absorber though other types of absorber may obviously be utilized without departing from the invention. In the absorber A the solution flows downwardly by gravity in contact with and in counterflow relationship with the inert gas refrigerant vapor mixture which is flowing upwardly through the vessel. The absorbing solution in the absorber is enriched in refrigerant content to produce so called strong liquor. This strong liquor is then conducted from the lower end of the absorber A through the conduit 34, the inner passage of the liquid heat exchanger 21 and conduit 35 into the upper portion of the analyzer D through which it flows into contact with and counterflow relationship to the vapors liberated in the generator B. This completes the absorbing solution circuit of the apparatus.

The so called lean inert gas refrigerant vapor mixture which is formed in the absorber A flows from the upper portion thereof through the conduit 36 into the suction or low pressure inlet of the circulating fan F wherein it is placed under pressure and discharged through the conduit 26 as described heretofore.

With the exception of the inert gas which is diverted through the conduit 27, the inert gas in conduit 26 enters the outer passage of a gas heat exchanger G, flows therethrough and is conducted therefrom by a conduit 37 to the principal evaporator 19. As shown in Figure 1, the liquid refrigerant supply conduit 18 actually joins the evaporator 19 at the point at which that evaporator connects to the inert gas supply conduit 37. The inert gas entering through the conduit 37 is under pressure and the evaporator is so designed that the inert gas circulates the liquid refrigerant through the evaporator as the liquid is evaporating to produce the refrigerating effect. This evaporator is of the general type disclosed in U. S. Patent No. 2,328,196 issued August 31, 1943. The evaporator is shown schematically in Figure 1 as consisting of a sinuous coil having two horizontal coil sections connected by a vertical lift pipe 38. It will be understood however that other forms of evaporator conduits may be utilized where design or refrigerating

conditions dictate their use. The inert gas and refrigerant liquid circulate through the various portions of the evaporator 19 in which the refrigerant liquid evaporates to produce a refrigerating effect. This process charges the inert gas with refrigerant vapor to produce the so called rich gas which is conveyed from the gas outlet portion of the evaporator through a conduit 39, the inner passage of the gas heat exchanger G and a conduit 40 to the lower end of the absorber A through which it passes in contact with the absorbing solution in a manner heretofore described. This process completes the principal inert gas circuit.

The inert gas which has traversed the evaporator 16 and is removed therefrom through the conduit 31 joins the conduit 40 adjacent the point at which it exits from the gas heat exchanger G.

From the foregoing it will be seen that the secondary inert gas circuit including the secondary absorber 25 and the low temperature evaporator 16 in effect comprise a by-pass or parallel circuit from the gas lift pump A to the absorber inlet around the principal evaporator 19.

The inert gas circuit is also used as a purging medium and pressure balancing device. For this purpose the condensers C and C' are respectively vented to the inert gas discharge conduit 39 of the evaporator 19 by the vent conduits 41 and 42 respectively. This purges the condensers of any non-condensable or non-condensed material which passes therethrough and also subjects the generator B and analyzer D substantially to the pressure prevailing at the suction inlet of the circulating fan F increased by the small pressure drops in the gas heat exchanger G and the absorber A. The pressure in these parts of the system is a substantially constant quantity in that it is principally governed by the substantially constant suction pressure of the circulating pump F. In a similar manner the upper portion of the solution reservoir S is vented by a conduit 43 to the suction conduit 36 of the circulating fan F. This serves also as a vent conduit for any vapors which may be liberated in the vessel S.

The principal evaporator 19 is provided with the usual overflow drain connection 45 which connects to the gas heat exchanger G.

The quantity of inert gas which is diverted through the secondary absorber gas lift pump 25 is very accurately controlled by that element to a fixed proportion of the total amount of inert gas discharged from the circulating pump F, hence a fixed proportion of the inert gas is always diverted from the pressure outlet of the circulating pump, is additionally reduced in refrigerant vapor content to a very low value, and is then supplied to the low temperature evaporator 16.

It is apparent from the foregoing that the present invention is particularly designed to provide a comparatively small volume of very highly stripped inert gas capable of producing extremely low refrigerating temperatures by intimately admixing such inert gas with a comparatively large volume of lean absorbing solution in an air cooled absorber under conditions such that complete stripping of the inert gas will only partially enrich the absorbing solution.

The apparatus includes an insulated refrigerator cabinet 50 having an opening 51 in a rear or side wall thereof through which the evaporating apparatus 16-19 and the various connecting conduits can be inserted into the interior of the insulated compartment. The opening 51 is closed by an insulated closure 52 which is carried by the

refrigerating system proper and is assembled with the rest of the cabinet only when it is also assembled with the refrigerating apparatus.

The evaporator 16 lies in the top portion of the interior of the refrigerating chamber 50 and the closure element 52 cooperated with an insulated partition 53 to form an insulated compartment 54 in the top of the cabinet structure. It is this compartment which forms the low temperature storage chamber. The partition 53 need not be as heavily insulated as the exterior walls of the cabinet structure 50 because it directly overlies the principal evaporator 19 and its lower surface is therefore maintained at a low temperature. By placing the coil 16 in the top of the chamber 54, all parts of that chamber are maintained at safe temperatures and the high level location of the conduit 16 tends to keep the air therein in circulation to maintain substantially uniform low temperatures.

In the form of the invention just described it has been found that the gas lift pump conduit 25 is a highly efficient absorber which ideally serves the purpose for supplying extremely stripped inert gas to a low temperature evaporator. This arrangement of parts, which imposes a double function upon the gas lift pump, is preferred where circumstances permit it, however, the latitude permitted the designer in this arrangement is somewhat limited because of the limit upon the amount of inert gas which can be passed through the gas lift pump. The primary limit is the quantity of gas required to perform the purely pumping function. The amount of gas may be varied somewhat by varying the point of juncture between the conduits 25 and 27, that is, the depth of immersion of the pump, but this again does not offer the designer a very wide choice, hence this type of apparatus, while preferred, is usable only where the needs of the low temperature compartment for inert gas fall within the limits of the amount of inert gas which can be utilized in the gas lift pump.

In the form of the invention shown in Figure 2 a construction is schematically illustrated which avoids the limitations inherent in the gas lift pump arrangement of Figure 1.

Only so much of the apparatus of Figure 2, as is different from the apparatus of Figure 1 is illustrated herein. It will be understood that all other parts of the apparatus are identical with those shown in Figure 1. Those portions of the apparatus actually illustrated in Figure 2 which are identical with portions of the apparatus of Figure 1 are identified with the same reference characters distinguished by the addition of a prime.

In the form of the invention illustrated in Figure 2 the solution reservoir doubles as an absorber. The lean inert gas discharging from the absorber A' flows through the conduit 36' into the circulating pump F' wherein it is placed under pressure and discharged through the conduit 26'. The major portion of this inert gas flows through the gas heat exchanger just as in the case of the conduit 26 in Figure 1 and then traverse the rest of its circuit identically therewith. A portion of the inert gas supplied to the conduit 26' flows through a conduit 60 which opens into the bottom of a combined solution reservoir and absorber 61. The conduit 60 extends into and includes a portion 62 lying within and adjacent the bottom of the solution reservoir 61. The portion 62 of the conduit 61 is provided with a large number of small perforations

so that inert gas can pass through the perforations and bubble into and through the body of solution contained in the solution reservoir 61. As in the Figure 1 construction a large volume of lean absorbing solution is used to strip a comparatively small volume of inert gas. The absorbing apparatus of Figure 2 is substantially as efficient as that shown in Figure 1 and has been found to produce inert gas stripped substantially to the same degree. The inert gas which is stripped in the absorber 61 is conveyed from the upper portion of the vessel 61 through the conduit 30' to the low temperature absorber in the manner described above in connection with Figure 1. Lean solution from the generator is supplied to the reservoir absorber 61 from the solution pre-cooling conduit 22', hence the leanest solution available in the system is supplied to the absorber-receiver 61. The absorbing solution which is somewhat enriched in the absorber-receiver 61 is conveyed to the principal absorber A' by a conduit 64 which includes a gas lift pump section 65. Pumping gas is supplied to the pump 65 by a conduit 66 which connects to the gas conduit 69. The inert gas which has traversed the gas lift pump 65 is admixed with the inert gas exiting from the absorber A'. In view of the fact that this gas is very lean it does no harm by being thus admixed with the lean inert gas discharging from the absorber A'.

This form of the invention provides a high degree of flexibility with respect to the quantity of the gas which is by-passed to the second absorber wherein it is substantially stripped of refrigerant vapor.

In this form of the invention the metering of inert gas diverted from the main inert gas circuit for supply to the low temperature evaporator is accomplished by a proper choice of size of the pipe 69, size of the perforations in the section 62 thereof and the depth by which the pipe section 62 is submerged in solution in the reservoir absorber 61. Once the capacity of the low temperature evaporator is determined the requisite quantity of gas is readily calculable. When that is known the resistance of the gas flow which must be offered by the total gas circuit comprising the evaporator 16 is then adjusted to give the requisite gas flow therethrough.

Referring now to Figure 3 there is disclosed a modification of the invention designed to provide highly stripped inert gas for the low temperature evaporator similarly to the form of the invention illustrated in Figures 1 and 2. Since this form of the invention is substantially identical with that illustrated in Figure 1 except in connection with certain portions of the secondary inert gas circuit only those portions thereof are illustrated which are necessary to disclose the differences therebetween. It will be understood that the remaining portion of the apparatus is identical in every respect with that illustrated in Figure 1. In this form of the invention those portions thereof which are identical with corresponding portions of the Figure 1 form of the invention are given the same reference characters distinguished by the addition of a double prime.

In Figure 3 the conduit 22" does not discharge directly into the solution reservoir S', instead it supplies the lean absorbing solution to an elongated tubular finned absorber vessel 70. This vessel is positioned below the liquid level in the boiler analyzer reservoir system and hence it is always filled with absorbing solution except such as may be displaced by inert gas forced into the

vessel 70. The solution flows through the vessel 70 and is conveyed therefrom through a U-shaped conduit 71 into the solution reservoir S'. From the solution reservoir S' the solution is conveyed to the absorber A" by the conduit 72 and gas lift pump 73. Pumping gas is diverted from the discharge conduit 26" of the circulating pump through a conduit 74 to operate the gas lift pump 73 and elevate the absorbing solution into the absorber A".

Inert gas which is to be stripped for operating the low temperature absorber is diverted from the conduit 26" by a conduit 75 which opens into the lower solution discharge end of the absorber vessel 70. Inert gas under pressure bubbles into and through the solution flowing through the vessel 70. With this arrangement a counterflow of the solution and inert gas is provided while the inert gas is bubbling into and through the solution. For this reason the vessel 70 must have a diameter large enough to prevent gas lift pump action so that the gas will not tend to pump the liquid in a reverse direction. Similarly the lower portion of the conduit 30' which conveys the inert gas to the low temperature evaporator must have a diameter sufficient to prevent the inert gas flowing therewith from lifting the solution in its lower end.

This form of the invention is particularly desirable for the largest capacity low temperature refrigerating unit because of the counterflow of solution and inert gas which the vessel 70 provides and also because of the comparatively large heat rejecting area which can be provided by the slightly inclined vessel 70.

In each of the three forms of the invention previously described the system is characterized by the provision of a structure in which a portion of the inert gas which has traversed the principal absorber is bubbled into and through the entire quantity of absorbing solution circulating in the system and is brought into most intimate contact therewith so that this comparatively small volume of inert gas is substantially completely stripped of its refrigerant vapor content by the comparatively large volume of solution into which it is introduced. This highly stripped inert gas then is chilled and relieved of entrained water vapor by being passed in heat exchange relationship with the principal evaporator of the system after which it contacts the anhydrous refrigerant liquid supplied to the low temperature evaporator.

In each instance the secondary or stripping absorption step is accomplished by an absorber which rejects its heat of absorption to the atmosphere.

The relative quantities of inert gas circulating through the primary and secondary absorbers, the change in concentration of the solution in the two absorbers and the proportion of refrigerant liquid evaporated in the primary and secondary evaporators are all subject to variation to meet different design and operating conditions.

As an example the following figures are those found to be approximately correct for a refrigerator having an eight cubic foot capacity within which there is provided an insulated compartment for storing sharp frozen food stuffs and an ice freezing housing adapted to support ice trays containing water to be frozen. The weak solution entering the secondary absorber contained approximately five percent ammonia. The solution leaving the secondary absorber and flowing to the primary absorber contained approximately

ten percent ammonia. The strong solution flowing to the generator contained approximately thirty-two percent ammonia. Approximately one-fourth of the total quantity of refrigerant liquid produced was supplied to the evaporator which refrigerated the sharp frozen food compartment. The inert gas exiting from the primary absorber and the inert gas entering the secondary absorber contained approximately ten percent by volume of ammonia. The inert gas leaving the secondary absorber and flowing to the evaporator for refrigerating the sharp frozen food compartment contained approximately one and one-half percent ammonia by volume. Approximately thirty percent of the inert gas discharged by the circulating pump was diverted to the secondary stripping absorber.

The foregoing figures are purely illustrative and are not limiting, all are subject to variation to meet the needs of variant design and operating conditions. In general, the weakest available solution in full volume and lean inert gas—such as inert gas which has traversed the primary absorber—should be supplied to the stripping absorber to facilitate its operation. The proportions of inert gas and refrigerant liquid diverted to the stripping absorber and low temperature evaporator respectively are variable to satisfy variant conditions, in general from fifteen to forty percent of the inert gas and from twenty to forty percent of the liquid refrigerant may be so diverted.

In any event the stripping absorber will be supplied with inert gas which contains a low percentage of refrigerant vapor and with the full stream of absorbing solution circulating through the system. Even if the inert gas were denuded of all admixed refrigerant vapor the solution resulting would be weak, that is, only partially enriched. The combination of inert gas which is initially lean and small in volume compared to the volume of inert gas customarily brought into contact with absorbing solution produces the extremely stripped inert gas provided for the low temperature evaporator in accordance with this invention. The quantity of refrigerant evaporated in the low temperature evaporator is not necessarily equal to the quantity absorbed in the stripping absorber since all of the inert gas circulating in the system passes through the primary absorber.

Under the conditions enumerated above the refrigerator was found to maintain temperatures in the region of 5° F. and below in the sharp frozen food compartment and to refrigerate the remaining portions of the cabinet construction in conventional temperature ranges and capacities.

The foregoing constructions are not well suited to gravity type systems in which the sole force available to circulate the inert gas is the density differential between the warm lean gas leaving the absorber and the cold rich gas leaving the evaporator. The pressure available in gravity systems is usually inadequate to bubble a portion of the gas into a body of absorbing solution. In such systems gas and liquid surface contact type absorbers are utilizable for this purpose; but these absorbers are inherently less effective as gas and liquid contact devices per se than the bubble type absorbers above described and will not strip the inert gas at the same degree. The advantages of the invention are realizable in gravity systems by using a secondary surface contact type absorber which is chilled to a low temperature by the primary evaporator in the system.

With this arrangement the requisite stripped inert gas can be obtained by passing all of the lean solution through the absorber into contact with a comparatively small quantity of initially lean inert gas.

Referring now to Figure 4 a modification of the invention is illustrated in which the inert gas circulation is by gravity as above described.

This form of the invention will be associated with an insulated refrigerator cabinet similar to that illustrated in connection with Figure 1. For simplicity in illustration the cabinet structure is indicated here by the broken line 78.

The apparatus comprises a generator 80 which is heated by any suitable means, not shown. The vapor formed from the rich solution in the generator 80 operates a vapor lift pump conduit 81 which serves to pump the lean solution into a separation vessel 82. The lean solution is conveyed from the vessel 82 to a secondary absorber 83 by the conduit 84, the inner path of the liquid heat exchanger 85, conduit 86, the inner path of a second liquid heat exchanger 87 and a conduit 88. The absorber 83 consists of a sinuous elongated conduit which is in contact substantially throughout its length with a sinuous elongated primary evaporator conduit 89. In the absorber 83 the lean absorbing solution flows into contact and counterflow relationship with inert gas which is circulating through the absorber in a comparatively small volume. The inert gas and absorbing solution flowing through the absorber 83 are maintained at a low temperature by the evaporator 89 and the refrigerant vapor content of the inert gas is reduced to a comparatively low value. The stripped inert gas is conveyed from the upper portion of the absorber 83 into the outer path of a gas heat exchanger 90 and then to the low temperature evaporator 91 through the conduit 92.

The low temperature evaporator 91 is positioned within an insulated low temperature chamber 94 which preferably will be positioned within the refrigerator cabinet.

The refrigerant vapor discharged into the separation chamber 82 is conducted therefrom to a condenser 95 by a conduit 96 which includes a finned rectifying section 97 to reduce the water vapor content of the vapors supplied to the condenser 95. The condensate formed in the condenser 95 flows through a U-shaped conduit 98 into the upper portion of the evaporator 91 through which it flows in counterflow relationship and contact with the inert gas flowing upwardly through the evaporator 91. The inert gas which has traversed the evaporator 91 flows through a portion of a conduit 99 exteriorly of the insulated chamber 94 in which place the inert gas evaporatively cools the liquid refrigerant flowing to the evaporator 91 before such liquid actually enters the chamber 94. Inert gas which has traversed the evaporator 91 is returned to the lower portion of the absorber 83 by the conduit 99 which passes through the inner passage of gas heat exchanger 90 and connects to the lower-most point in the absorber 83. This completes the secondary inert gas circuit which links the low temperature evaporator 91 and the absorber 83.

The quantity of the refrigerant actually evaporated in the evaporator 91 is comparatively small accounting for approximately twenty to forty percent of the total quantity of refrigerant condensed in condenser 95 depending upon the design and operating conditions.

The absorbing solution which has traversed the

11

absorber 83 is conveyed therefrom to the principal absorber 100 by the conduit 101; liquid heat exchanger 87 and the U-shaped gas seal conduit 102.

The partially enriched absorbing solution supplied to absorber 100 flows downwardly therethrough by gravity in surface contact with and in counterflow relationship with inert gas flowing upwardly through that absorber. The absorbing solution is enriched in the absorber 100 to form the so called strong liquor. After traversing absorber 100 the enriched solution is conveyed therefrom to the generator 80 by way of conduit 103, solution reservoir 104, conduit 105, solution heat exchanger 85 and conduit 106 to complete the absorbing solution circuit.

Inert gas deprived of refrigerant vapor in the absorber 100 is conveyed therefrom to the lower portion of the principal evaporator 89 by way of conduit 108, the gas heat exchanger 109 and conduit 110. The inert gas flows upwardly through the evaporator 89 in contact with and counterflow relationship with liquid refrigerant flowing downwardly therethrough. Liquid refrigerant which is unevaporated in the evaporator 91, the major portion of the liquid condensed in the condenser 95, flows from the lower portion thereof to the upper portion of the evaporator 89 by way of the conduit 111, the heat exchanger 112, which surrounds one leg of conduit 98 to pre-cool liquid refrigerant flowing to evaporator 91, and trap sealed conduit 113. The evaporator 89 refrigerates the ice freezing compartment 114, the absorber 83, and the air within the food storage compartment of the refrigerator cabinet. After traversing the evaporator 89 the enriched inert gas is returned to the absorber 100 by way of the conduit 116, the gas heat exchanger 109 and the conduit 117 to complete the second inert gas circuit.

A vent conduit 118 extends from the lower end of the condenser 95 to the rich gas conduit 116 of the principal inert gas circuit in order to relieve the condenser system of non-condensable and non-condensed products which may pass therethrough.

For simplicity this form of the invention has been illustrated with a single condenser. It is however contemplated that the evaporator 91 shall be supplied with anhydrous refrigerant by a double condenser arrangement such as that illustrated in connection with Figure 1.

In this form of the invention the leanest solution in the system is first brought into contact with inert gas in a secondary inert gas circuit under conditions such that the solution is called upon to strip only a comparatively small volume of inert gas which does not contain a large amount of refrigerant vapor initially. The refrigerant vapor concentration range in the inert gas circuit linking the evaporator 91 and the secondary absorber 83 will be in a comparatively narrow range and of low absolute value. Thus the inert gas exiting from the absorber 83 may contain no more than three or four percent refrigerant vapor by volume and be enriched to ten to fifteen percent of refrigerant vapor by volume in the evaporator 91. The foregoing figures constitute the approximate limits of the concentration range which exists in the secondary inert gas circuit. On the other hand, the absorbing solution entering the absorber 83 may have a refrigerant content of five or six percent and be increased to no more than ten or twelve percent in its passage therethrough.

12

In the principal inert gas circuit linking the principal evaporator 89 and the absorber 100 the lean inert gas leaving the absorber may contain as much as ten or eleven percent refrigerant vapor by volume and be enriched in the principal evaporator to a much higher figure depending on the total refrigerating load. The absorbing solution entering the absorber 100 will have the same concentration as the solution leaving the absorber 83 and its concentration may be increased in the absorber 100 to approximately thirty-two percent refrigerant.

In this form of the invention like those previously described the quantity of inert gas circulating per unit of time in the low temperature circuit may equal fifteen to forty percent of the quantity of inert gas circulating per unit of time in the principal inert gas circuit. Since all of the absorbing solution circulating through the system is brought into absorbing relation with this comparatively small volume of comparatively lean inert gas in a low temperature absorber, the desirable highly stripped inert gas is provided for the low temperature evaporator and the solution is only partially enriched. The solution would be only partially enriched if it absorbed all the refrigerant vapor admixed with the inert gas.

In accordance with the present invention I have provided constructions by which extremely low temperature refrigeration can conveniently be secured in inert gas three fluid type absorption refrigerating systems. Where the design of the systems permits, an extremely highly stripped inert gas can be supplied to the low temperature evaporator by an absorber which is air cooled. This can be accomplished effectively by bubbling or introducing a comparatively small quantity of low refrigerant vapor content, lean inert gas into all of the absorbing solution circulating in the system so that substantially complete stripping of the gas does not greatly enrich the solution, that is, the solution is lean solution as that term is used in this art even after it has traversed the initial absorber. In systems in which the aforementioned highly efficient type of absorber is not feasible it has been found desirable to cool the absorber for the low temperature evaporator by placing the same in heat exchange relationship with the principal evaporator of the system. In this arrangement also a small volume of low refrigerant content inert gas contacting a large volume of absorbing solution is used to strip the inert gas without unduly enriching the absorbing solution.

It will be understood that all of the contact type absorbers such as A, A', A"; 83 and 100 above described may be, and preferably are, provided with known types of inserts, baffles and the like to agitate the inert gas and absorbing solution which are flowing therethrough.

While I have illustrated and described the invention in considerable detail, it is to be understood that various changes may be made in the arrangement, proportion and construction of parts without departing from the spirit of the invention or the scope of the appended claims.

I claim:

1. In a refrigerating apparatus of the pressure equalized absorption type, a pair of evaporators, an absorber, a generator, means for liquefying refrigerant vapor evolved in said generator and for supplying refrigerant liquid to said evaporators, means for conducting inert gas through said absorber and to one of said evaporators, means

for conveying absorbing solution from said generator to said absorber including a gas lift pump, means for introducing inert gas into said gas lift pump to operate the same and means for conveying pumping gas which has traversed said gas lift pump to said second evaporator.

2. In a refrigerating apparatus of the pressure equalized absorption type, a pair of evaporators, an absorber, a generator, means for liquefying refrigerant vapor evolved in said generator and for supplying refrigerant liquid to said evaporators, means for conducting inert gas through said absorber and to one of said evaporators, means for conveying absorbing solution from said generator to said absorber including a gas lift pump, means for withdrawing a part of the inert gas which has traversed said absorber from the means conducting inert gas to said one evaporator and for introducing such withdrawn gas into said gas lift pump to operate the same and means for conveying pumping gas which has traversed said gas lift pump to said second evaporator.

3. That improvement in the art of refrigeration which includes the steps of applying heat to a solution of refrigerant in absorbent to liberate refrigerant vapor therefrom, flowing the solution from which refrigerant vapor has been liberated into contact with an inert gas refrigerant vapor mixture to reduce the refrigerant vapor content of said mixture to the minimum value of a first concentration range, flowing the inert gas refrigerant vapor mixture into contact with refrigerant liquid to increase its refrigerant vapor content to the maximum value in said first concentration range, flowing the partially enriched absorbing solution into contact with an inert gas refrigerant vapor mixture having a larger volume than the inert gas refrigerant mixture in said first concentration range to reduce the concentration of such mixture to the minimum value in a second concentration range which is higher than said first mentioned minimum value, flowing the inert gas of said minimum value of said second concentration range into contact with refrigerant liquid to increase the refrigerant concentration to the maximum value of said second concentration range which is higher than the maximum value of said first concentration range.

4. In a refrigerating apparatus of the pressure equalized absorption type including a first evaporator, a first absorber connected to supply inert gas to said first evaporator, a second evaporator, a second absorber connected to supply inert gas to said second evaporator, means for flowing lean absorbing solution through said first absorber and thence through said second absorber, means for conducting a first body of inert gas refrigerant vapor mixture to said first absorber, means for conducting a second larger body of inert gas refrigerant vapor mixture to said second absorber and said means for conducting inert gas from said first absorber to said first evaporator passing in heat exchange relation with said second evaporator to condense absorbent vapors from said inert gas.

5. That improvement in the art of refrigeration which includes the steps of applying heat to a solution of refrigerant in an absorbing solution to liberate refrigerant vapor therefrom until the absorbing solution contains approximately five percent absorbed refrigerant, conducting said absorbing solution containing approximately five percent absorbed refrigerant into absorbing contact with an inert gas refrigerant vapor mixture containing not more than twelve percent refrigerant

erant vapor by volume and absorbing refrigerant from said mixture into said absorbing solution to reduce the refrigerant vapor content of said mixture to not more than four percent refrigerant by volume and increasing the refrigerant content of said absorbing solution to approximately ten percent, conducting said absorbing solution containing approximately ten percent refrigerant into absorbing contact with an inert gas refrigerant vapor mixture to absorb refrigerant therefrom to reduce the refrigerant content of said mixture to approximately ten percent refrigerant vapor by volume and to increase the refrigerant content of said absorbing solution to approximately thirty-two percent, flowing said inert gas containing not more than four percent refrigerant vapor into contact with refrigerant liquid to produce a first refrigerating effect, and flowing said inert gas containing approximately ten percent refrigerant vapor into contact with refrigerant liquid to produce a second refrigerating effect at a higher temperature level than said first refrigerating effect.

6. In an absorption refrigerating apparatus, a generator, a first air cooled absorber positioned below the surface level of absorbing solution in said generator, a second air cooled absorber, means for circulating absorbing solution through said generator and said first and second absorbers serially in the order named, first and second evaporators, means for conducting inert gas from said second evaporator to said second absorber, means for placing inert gas under pressure, means for conducting inert gas from said second absorber to said pressure creating means, means for conveying a portion of the inert gas placed under pressure by said pressure creating means to said second evaporator and for introducing another portion of the inert gas under pressure into the absorbing solution in said first absorber, and means for conveying inert gas from said first absorber to said first evaporator, and means for supplying refrigerant liquid to said evaporators.

7. In an absorption refrigerating apparatus, a generator, a first air cooled absorber comprising an elongated air cooled conduit, a second air cooled absorber, means for circulating absorbing solution through said generator and said first and second absorbers serially in the order named, first and second evaporators, means for conducting inert gas from said second evaporator to said second absorber, means for placing inert gas under pressure, means for conducting inert gas from said second absorber to said pressure creating means, means for conveying a portion of the inert gas placed under pressure by said pressure creating means to said second evaporator and for introducing another portion of the inert gas under pressure into the absorbing solution in said first absorber in a manner to pass into and through the absorbing solution therein contained and to flow through said first absorber in counterflow relation to the absorbing solution, means for conveying inert gas from said first absorber to said first evaporator and means for supplying refrigerant liquid to said evaporators.

8. Refrigerating apparatus comprising a cabinet structure including food storage and low temperature refrigerating chambers insulated from each other, a low temperature evaporator in the top portion of said low temperature refrigerating chamber, a second evaporator arranged to refrigerate said food storage chamber, a generator, a first condenser, means for conveying refrigerant vapors from said generator to said first condenser,

means for conveying refrigerant liquid condensed in said first condenser into heat exchange with said vapor conveying means and to said second evaporator, a second condenser, means for conducting vapors evolved in said refrigerant liquid conveying means to said second condenser, means for conveying refrigerant liquid from said second condenser to said first evaporator, a pair of absorbers, means for conducting inert gas from said evaporators to one of said absorbers, means for conducting a part of the inert gas which has traversed said one absorber directly to said one evaporator and the remainder of said inert gas through the other of said absorbers and to said low temperature evaporator, and means for circulating absorbing solution from said generator through said other and said one absorber in that order and back to said generator.

9. A refrigerating apparatus comprising a cabinet structure including a low temperature insulated chamber and a higher temperature insulated chamber, a freezing compartment in said higher temperature chamber, an absorption refrigerating apparatus associated with said cabinet structure including a first evaporator for refrigerating said low temperature chamber, a second evaporator for refrigerating said compartment and said higher temperature chamber, first and second air cooled absorbers positioned exteriorly of said insulated chambers, a generator, means for conducting absorbing solution through said first and second absorbers serially in the order named, means providing a circuit for inert gas including said second evaporator and said second absorber, and means forming a by-pass circuit for inert gas around said second evaporator in which a portion of the inert gas which has traversed said second absorber is conducted through said first absorber and said first evaporator.

10. Refrigerating apparatus of the pressure equalized type charged with a refrigerant, an absorbent for the refrigerant and an inert gas comprising: a low temperature evaporator, a high temperature evaporator, an auxiliary absorber, a principal absorber, means for generating refrigerant vapor from solution in said absorbent, means for liquefying refrigerant vapor evolved in said generating means and for supplying refrigerant liquid to said evaporators, means providing for circulation of said absorbent from said generating means through said auxiliary absorber and then through said principal absorber back to said generating means; means providing a plurality of paths of flow of inert gas and refrigerant vapor mixture in which the refrigerant vapor content of the mixture varies from a maximum to a minimum value, one of said paths of flow including means for conveying a part of said mixture having a refrigerant content below said maximum value from said principal absorber through said high temperature evaporator to increase the refrigerant content of the mixture to said maximum value, and another of said paths of flow including means for conveying another part of said mixture having a refrigerant content above said minimum value through said auxiliary absorber to reduce the refrigerant content thereof to said minimum value and to flow said mixture of minimum refrigerant content through said low temperature evaporator.

11. Refrigerating apparatus of the pressure equalized type charged with a refrigerant, an absorbent for the refrigerant and an inert gas comprising: a low temperature evaporator, a high temperature evaporator, an auxiliary ab-

sorber, a principal absorber, means for generating refrigerant vapor from solution in said absorbent, means for liquefying refrigerant vapor evolved in said generating means and for supplying refrigerant liquid to said evaporators, means providing for circulation of said absorbent from said generating means through said auxiliary absorber and then through said principal absorber back to said generating means; means providing a plurality of paths of flow of inert gas and refrigerant vapor mixture in which the refrigerant vapor content of the mixture varies from a maximum to a minimum value, one of said paths of flow including means for conveying a major proportion of the total quantity of mixture circulating in said apparatus per unit of time and having a refrigerant content intermediate said maximum and minimum values from said principal absorber through said high temperature evaporator where-
20 in the refrigerant vapor content of the mixture is increased to said maximum value, and another of said paths of flow including means for conveying a minor proportion of the total quantity of mixture circulating in said apparatus per unit of time and having a refrigerant vapor content intermediate said maximum and minimum values through said auxiliary absorber to reduce the refrigerant content of the mixture to said minimum value and then through said low temperature evaporator.

12. Refrigerating apparatus of the pressure equalized absorption type including, a first evaporator, a first absorber of the type normally containing a body of absorbing solution in operation, a second evaporator, a second absorber, means for flowing lean absorbing solution through said first absorber and thence through said second absorber, means providing a plurality of paths of flow of inert gas for circulating inert gas through said evaporators and said absorbers including means for introducing a minor proportion of the total quantity of inert gas circulating in the apparatus per unit of time into said first absorber below the liquid level therein to pass into and through the absorbing solution therein and for then conveying such inert gas into said first evaporator, and means for flowing the major proportion of the inert gas circulating in said apparatus per unit of time through said second evaporator and then through said second absorber.

13. That improvement in the art of refrigeration which includes the steps of applying heat to a solution of refrigerant in an absorbent having a maximum refrigerant content to evolve refrigerant vapor and reduce the refrigerant content of said absorbent to a minimum value, liquefying the refrigerant vapor so evolved, contacting absorbent of said minimum refrigerant content with a mixture of inert gas and refrigerant vapor having a refrigerant content such that the refrigerant content of the solution is increased to a value below said maximum value and the refrigerant content of the inert gas is reduced to a minimum value, evaporating a portion of said liquefied refrigerant into said inert gas of minimum refrigerant content to produce a first refrigerating effect, contacting said solution which has had its refrigerant content increased by said first mentioned inert gas refrigerant vapor mixture with a second inert gas refrigerant vapor mixture having a higher refrigerant vapor content than the initial refrigerant vapor content of said first mentioned inert gas refrigerant vapor mixture to increase the refrigerant content of

17

said solution to said maximum value and to reduce the refrigerant content of said second mentioned inert gas refrigerant vapor mixture, and evaporating another part of said liquefied refrigerant into said second mentioned inert gas refrigerant vapor mixture to increase the refrigerant vapor content thereof to a maximum and to produce a second refrigerating effect.

14. A refrigerating apparatus comprising a cabinet structure including a low temperature insulated chamber and a higher temperature insulated chamber, a freezing compartment in said higher temperature chamber, an absorption refrigerating apparatus associated with said cabinet structure including a first evaporator for refrigerating said low temperature chamber, a second evaporator for refrigerating said compartment and said higher temperature chamber, a first absorber of the type normally containing a body of liquid in operation positioned exteriorly of said insulated chambers, a second absorber positioned exteriorly of said insulated chambers, a generator, means for conducting absorbing solution from said generator through said first and second absorbers serially in the order named and back to said generator, means for circulating an inert gas through and between said second absorber and said second evaporator, and means for conducting a portion of the inert gas which has traversed said second absorber into said first absorber below the liquid level therein and thence through said first evaporator back to said second absorber.

15. Refrigerating apparatus of the pressure equalized type charged with a refrigerant, an absorbent for the refrigerant and an inert gas comprising: a low temperature evaporator, a high temperature evaporator, an auxiliary absorber, a principal absorber, means for generating refrigerant vapor from solution in said absorbent, means for liquefying refrigerant vapor evolved in said generating means and for supply-

18

ing refrigerant liquid to said evaporators, means providing for circulation of said absorbent from said generating means through said auxiliary absorber and then through said principal absorber back to said generating means; means for flowing inert gas from said evaporators to said principal absorber means for flowing inert gas from said principal absorber to said high temperature evaporator, and means for flowing a minor part of the inert gas which has traversed said principal absorber through said auxiliary absorber and thence through said low temperature evaporator.

16. Apparatus according to claim 10 including means for conducting said inert gas refrigerant vapor mixture of maximum refrigerant content from said high temperature evaporator to said principal absorber and said means for conducting inert gas refrigerant vapor mixture to said auxiliary absorber is connected to receive said mixture from said low temperature evaporator.

17. Apparatus according to claim 10 in which said auxiliary absorber is in heat exchange relation with said principal evaporator.
